TUNING DEVICE

Eric O. Peterson, Bridgeport, and Edward W. Forstrom, Stratford, Conn., assignors to General Electric Company, a corporation of New York

Application September 20, 1946, Serial No. 698,350

5 Claims. (Cl. 171—242)

1

Our invention relates to apparatus for tuning high frequency circuits and it has for its primary object to provide a new and improved tuner assembly which is simple in construction, and yet provides accurate tuning over a wide frequency band.

It is still another object of our invention to provide a new and improved tuning device which is adapted to be manufactured in large quantities from a minimum number of component parts which are easily assembled and disassembled, which is inexpensive in construction, and yet which constitutes a tuning device reliable in operation.

The novel features which we believe to be characteristic of our invention are set forth with particularity in the appended claims. The invention itself, however, both as to its organization and method of operation, together with further objects and advantages thereof, may best be understood by reference to the following description taken in connection with the accompanying drawing in which Fig. 1 is a perspective view, partly in section, of our improved tuning device and Fig. 2 is an exploded view of the device of Fig. 1.

Referring to Figs. 1 and 2 jointly, we have illustrated therein at 1 a portion of the chassis normally employed in radio and other high frequency equipment which comprises a flat metallic surface and upon which is supported a tuning device comprising a pair of insulating supports 2, 3, a pair of juxtaposed peripherally incomplete metallic loops 4, 5, and a movable metallic vane 6. The insulating supports 2, 3 are identical in construction and may be formed by molding a suitable insulating material, such as a phenolic resin. The supports 2, 3 are provided with an accurately located vertical slot 7 adapted to slidably receive and support the vane 6. Bosses 8 at the bottom of each of the supports are adapted to fit into two parallel slots 9 pierced or otherwise cut in the chassis 1. We provide means for accurately controlling the spacing between the loops 4, 5 which comprise two pairs of recesses 10, 11 and 12, 13 positioned, respectively, on opposite sides of the slot 7 to receive, respectively, one of the metallic arms 14, 15 projecting outwardly from the loops 4, 5. To this end, the insulators are accurately molded so that the apertures therein are positioned with a tolerance of approximately 0.5% so that the spacing between the loops 4, 5 is held to an accuracy of 1%.

The loops 4, 5 may be formed by stamping a

2

flat piece of a suitable metal, such as copper or brass. In stamping the loops 4, 5, we provide means for accurately positioning the loops laterally on the assembled unit which comprises on each of the loops four shoulders 16 adjacent the arms 14, 15 and which are adapted to fit against the outer surface of the supports 2, 3. To assist in this lateral positioning, the outer vertical edges 17 of the loops are cut back so that they do not project outwardly from the center of the respective loop as far as the shoulders 16. At the lower end of each loop there is provided a terminal post 18 which is adapted to extend through apertures 19 provided in the chassis 1. The terminal posts, when assembled in position on the chassis, extend through the apertures 19 so that connection may be easily made to the loops. Means are also provided for serially connecting the loops 4, 5 which comprise an eyelet 20 which is adapted to be inserted in apertures 21 provided in an inwardly extending leg 22 of each of the loops and to be soldered thereto.

In order that the components may be held in assembled relation and also securely supported on the chassis 1, we provide a U-shaped metallic spring 23 having vertical arms 24 adapted to pass through slots 25 provided in the chassis 1. The arms 24 are further adapted to lie in the slots 26 provided on the outer surface of the supports 2, 3 and, at their upper ends, have inwardly directed portions 27 which are received in recesses 28 provided at the upper ends of slots 26 and engage a shoulder 29 formed by these recesses. The portion 30 of the spring 23 which lies below the chassis 1 is formed as a Z in order to provide both for lateral adjustment of the arms 24 and also to avoid the possibility of any conductive connection or contact with the terminal posts 18. Adjustment of the inductance of the device is effected by means of an operating rod 31 attached to an aperture 32 provided in the upper part of the vane 6. In such tuning adjustment, the vane slides freely in the slots 1. It will be understood, of course, that in the usual radio equipment employing a device of this type, additional means are provided to hold it in adjusted position by controlling the operating rod 31.

In assembling our tuning device, the loops 4, 5 are oriented by rotating one of the loops through 180° with respect to the other and the arms 14, 15 are inserted in the recesses 10—13 of the supports 2, 3, which are arranged to have their slotted surfaces in opposed relation. Such

orientation of the loops 4, 5 causes alignment of the apertures 21 so that the eyelet 28 may be inserted and soldered therein, thereby accurately spacing the loops 4, 5 for all further purposes. The terminal posts 18 and the bosses 8 are positioned in the openings 19 and slots 9, respectively, locating the assembly on the chassis. The arms 24 of the spring 23 are then slipped through the slots 25 with the portion 30 being located on the opposite side of the chassis from the assembled device. The inwardly directed portions 27 of the arms 24 are snapped into position over the shoulder 29 to pull the assembly tightly to the chassis. At the same time, the lateral pressure provided by arms 24 compresses the supports 2, 3 laterally until they engage the shoulder 16 of the metallic loops 4, 5, accurately positioning the loops laterally.

An important advantage of our improved tuning device is that it permits rapid production of variable inductances in large quantities without any loss in accuracy of the tuning characteristic. The device is extremely simple to assemble and, once assembled, may be disassembled without any effect on the tuning characteristic. Thus, the eyelet 28 holds the loops firmly in position and the composite construction is such that accurate alignment of all parts is provided even when the device is reassembled.

While we have shown a particular embodiment of our invention, it will of course be understood that we do not wish to be limited thereto since various modifications may be made, and we contemplate by the appended claims to cover any such modifications as fall within the true spirit and scope of our invention.

What we claim as new and desire to secure by Letters Patent of the United States is:

1. A variable inductance comprising a pair of spaced insulators having parallel opposing surfaces and outer surfaces, each of said opposing surfaces having a slot therein and recesses on opposite sides of said slots, a pair of metallic plates having central openings and a peripheral gap, said plates having arms extending into said recesses, a metallic vane arranged for rectilinear movement in said slots, and resilient means engaging said outer surfaces to maintain said arms positioned in said recesses.

2. A variable inductance comprising a pair of spaced insulators having parallel opposing surfaces and outer surfaces, each of said opposing surfaces having a slot therein and recesses on opposite sides of said slots, a pair of metallic plates having central openings and a peripheral gap, said plates having arms extending into said recesses, a metallic vane arranged for rectilinear movement in said slots, and resilient means engaging said outer surfaces to maintain said arms positioned in said recesses, said plates having shoulders adjacent said arms for engaging said opposing surfaces.

3. A variable inductance device comprising a pair of spaced insulators having opposing faces having vertical slots therein and a plurality of recesses on opposite sides of said slots, a pair of metallic plates having a central aperture therein and a plurality of outwardly extending arms adapted to be received in said recesses to restrain said plates against movement in a plane

normal to the surfaces thereof, a metallic vane arranged for rectilinear movement in said slots, each of said insulators having a recess on the outer surface thereof, and resilient means adapted to engage said outer recesses for clamping said insulators and said plates in assembled relation, said plates having shoulders adjacent said arms engaging said opposing faces to limit the lateral movement of said insulators.

4. A variable inductance comprising a pair of parallel insulators having on their opposing faces a longitudinal slot and a plurality of recesses on opposite sides of said slot, a pair of peripherally incomplete loop-like inductors having an inwardly directed leg and a plurality of outwardly extending arms, said inductors being so oriented that said legs are overlapping, conductive means connecting said overlapping legs, said arms being disposed in said recesses, said inductors having shoulders adjacent said arms adapted to engage said opposing surfaces, a flat metallic vane supported for longitudinal movement in said slot, said slot being of such length that said vane in its lowermost position lies above said connecting means, and resilient means engaging the outer surfaces of said insulators and said inductors in assembled relation.

5. A variable inductance for high frequency apparatus comprising a support having a plurality of parallel slots therein and a plurality of openings intermediate said slots, a pair of insulators mounted on said support and having portions extending into said slots, said insulators having opposing faces having a vertical guide therein and recesses on opposite sides of said guide, a pair of peripherally incomplete loop-like inductors having outwardly extending arms adapted to be received in said recesses and an inwardly extending leg, said inductors being oriented so that said legs are overlapping, rigid conductive means connecting said overlapping legs for maintaining said inductors in parallel spaced relation, said inductors having terminals extending through said openings whereby said inductors may be connected in a desired circuit, a metallic vane movably supported in said guide, said guide terminating in a point such that the lowermost position of said vane is above said rigid connecting means, said support having a pair of apertures disposed on opposite sides of said slots, said insulators having shoulders on their external surfaces, and resilient means extending through said apertures and engaging said shoulders, said resilient means having a portion lying on the opposite side of said support from said insulators shaped to avoid contact with said terminals.
